UNITED STATES PATENT OFFICE

114,615

DESIGN FOR A TEXTILE FABRIC

Theresa Emmerich, New York, N. Y.

Application March 20, 1939, Serial No. 83,710

Term of patent 7 years

To all whom it may concern:

Be it known that I, Theresa Emmerich, a citizen of the United States and a resident of New York, in the county of New York and State of New York, have invented a new, original, and ornamental Design for a Textile Fabric, of which the following is a specification, reference being had to the accompanying drawing, forming part thereof, and in which the figure is a plan view of a textile fabric showing my new design.

I claim:

The ornamental design for a textile fabric, substantially as shown.

THERESA EMMERICH.
